(57) **CLAIM**

The ornamental design for a nose hair trimmer, as shown and described.

DESCRIPTION

FIG. 1 is a front perspective view of a nose hair trimmer, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view of a nose hair trimmer, shown in another configuration.

The broken lines in the drawings illustrate the portions of the nose hair trimmer, which form no part of the claimed design. The nose hair trimmer and the cap have been shown separately in FIG. 9 to show aspects of the design that are not visible when combined.
